UNITED STATES PATENT OFFICE

HARWOOD BEEBE, OF SPARTANBURG, SOUTH CAROLINA

ROADWAY AND METHOD OF CONSTRUCTING THE SAME

Application filed July 24, 1928. Serial No. 294,978.

The present invention relates to improvements in road constructions and has for its principal object to provide a roadway consisting of spaced wooden header curbings between which is built a foundation of top soil and sand clay or other similar material as a base for bituminous types of wearing surfaces.

A further object is to provide a roadway 10 that includes supplemental header curbs that are secured on the upper edges of the main header curbings to provide an abutment for the asphalt surface.

Still a further object is to provide a roadway 15 construction wherein a foundation may be used initially as a road surface to secure a well bonded top soil road bed, which will always conform to a true line and grade, after which the material forming the foundation 20 will be suitable as a base for an asphalt top surface, and the employment of the supplemental header curbs will allow the formation of a square edge at the sides of the asphalt top.

Still a further object is to provide a roadway and an improved method of constructing the same which is simple and inexpensive and the road will be strong and durable.

Other objects of the invention will become 30 apparent as the nature of the invention proceeds and when taken in connection with the accompanying drawings.

In the accompanying drawings, forming 35 a part of this application and wherein like reference characters designate like parts throughout the several views:

Figure 1 is a sectional view showing the first step in building my improved roadway, wherein spaced wooden header curbs are 40 placed in an edgewise manner on the finished sub-grade.

Figure 2 is a similar section showing the foundation in place between the header curb and the formation of earth shoulders at the 45 outer sides of the header curbs.

Figure 3 is a similar section showing the attachment of a supplemental curb to the upper edges of the main header curb, prior to the application of the bituminous wearing surface.

Figure 4 is a cross sectional view through a completed roadway constructed in accordance with the present invention and showing the manner in which the bituminous wearing surface covers the foundation and abuts the inner opposed side edges of the supplemental header curb.

Figure 5 is an enlarged fragmentary side elevation showing the connecting means between the adjacent sections of the main header curb and the manner in which the supplemental header curbs are attached to the upper edges of the main header curbs.

Figure 6 is an edge elevation looking into one end of one of the sections of the main header curbs and the supplemental header curb which is secured thereon, and

Figure 7 is a group perspective of the adjacent ends of one pair of sections of the main header curbs.

In the drawings, wherein for the purpose of illustration is shown the preferred embodiment of my invention, the numerals 1 and 2 designate the spaced wooden header curbs that are of rectangular formation and each of these header curbs includes a plurality of sections denoted by the reference characters 3 and 4 respectively, with reference more particularly to Figures 5 and 7. The adjacent ends of the sections of each main header curb are formed with cooperating dowel pins 5, and sockets 6, whereby said sections may be connected together in abutting relation and so that said sections will be disposed in alignment with each other.

The sectional main header curbs are disposed in an edgewise manner and the lower edges of the header curb extend slightly below the sub-grade A, as shown in Figure 1. With the main header curbs positioned in the

manner as shown in Figure 1, the road foundation 7 which consists of a mixture of top soil, sand, clay, clay gravel, or other similar material, fills up the space between the header curbs and this material is brought to a true contour even with the header curbs, parallel to the proposed finished grade. The earth shoulders 8 are then built up at the outer sides of the respective header curbs and these shoulders are thoroughly compacted.

The road as thus far constructed can be thrown open to traffic and machined and worked as necessary to secure a well-bonded top soil road bed. When using a road machine, the timber header curbs shall be used as a gauge for maintaining the proper surface contour of the road. The road shall be kept as near as possible to the proper contour at all times.

When the road becomes thoroughly bonded under traffic and weather conditions, so that it is suitable to serve as a base for a bituminous wearing surface, supplemental wooden header curbing strips 9 and 10 are secured on the upper edges of the sectional main header curbings 1 and 2 respectively, by driving nails, such as are shown at 11, through the supplemental header curbings into the respective main header curbs as shown in Figures 5 and 6 of the drawings.

These supplemental header curbs are also constructed in section and are of the same width as the width of the sections comprising the main header curbs. These supplemental header curbing strips are rectangular in cross section and the height of the supplemental header curbing strips depends upon the thickness of the proposed asphalt top wearing surface.

If the upper edges of the main header curbs have become worn under traffic or by the use of road machines to the extent that a proper bearing surface cannot be secured for the supplemental header curbing strips, then the main header curbs can be trued down to provide a smooth surface for properly receiving the supplemental header curbing strips.

When the parts are arranged as shown in Figure 3 of the drawings, and the surface of the road bed has been thoroughly cleaned, the finishing asphalt wearing surface 12 shall be placed upon the road, the same to conform to the finished contour of the pavement. The shoulders of the road outside of the header curbs shall be built up to conform with the road's asphalt surface, as indicated at 13, in Figure 4.

The use of the rectangular shaped supplemental header curbs will provide a means whereby a square edge will be formed at each side of the asphalt wearing surface 12, instead of forming the wearing surface with a tapered edge, which is always subject to breakage, due to its thinness.

A road constructed in the manner as de-

scribed above will not only be strong and durable, but will also be inexpensive.

The use of the timber header curb enables the base of foundation of the road to be held in a rigid position thereby preventing any sloughing away of the material. The header curbs will also protect the soil base from any circulation of water under the road surface, which would soften the base and allow failure of the pavement. By building up the header curbs in the manner as shown, the top soil or foundation of the road may be built up and a true surface maintained under traffic until time for scraping the bituminous wearing surface, and in this manner, a bond of the base can be secured in such a manner that it is impossible to obtain by mechanical means.

While I have shown the preferred embodiment of my invention, it is to be understood that various changes in the size, shape and arrangement of parts may be resorted to, without departing from the spirit of the invention or the scope of the appended claims.

I claim:

1. A method of constructing a roadway consisting in setting spaced header curbs on a finished sub-grade, covering the sub-grade between the curbs with a base forming composition, forming earth shoulders at the outer sides of the curbs, subsequently building up the header curbs and finally covering the base with a bituminous wearing surface, the edges of the wearing surface abutting the built up portions of the header curbs.

2. A roadway comprising spaced header curbs extending upwardly from the finished sub-grade, and a foundation of suitable material compressed between the curbs, the top surface of the foundation being arranged in the contour of the upper edges of the header curbs, shoulders built up at the outer sides of the curbs, supplemental header curbing strips secured on the upper edges of the aforementioned header curbs, and a wear surface material covering the foundations abutting the supplemental header curbing strips, the supplemental header curbing strips being rectangular in cross section to provide square side edges for the said wearing surface.

3. A roadway comprising spaced header curbs extending upwardly from a finished sub-grade, a foundation of suitable material compressed between the curbs, the top surface of the foundation being arranged in the contour of the upper edges of the header curb, shoulders built up at the outer sides of the curbs, supplemental header curbing strips secured on the upper edges of the aforementioned header curbs, a wear surface material covering the foundation abutting the supplemental header curbing strip, said shoulders being built to meet the supplemental face of the curbing strip.

4. A roadway comprising spaced sectional

header curbs extending upwardly from a finished sub grade, a foundation of suitable material compressed between said curbs, the top surface of the foundation being arranged in the contour of the upper edges of the header curbs, supplemental sectional header curbing strips secured on the upper edges of the aforementioned header curbs, and a wear surface material covering the foundation abutting the supplemental header curb strip.

In testimony whereof I affix my signature.
HARWOOD BEEBE.
